OTHER PUBLICATIONS

U.S. Appl. No. 17/829,656, filed Jun. 1, 2022, titled "Roller Shade Hem Bar Assembly".

Primary Examiner — Clare Ann Gannon

(74) Attorney, Agent, or Firm — Crestron Electronics, Inc.

(57) **CLAIM**

The ornamental design for a roller shade bar, as shown and described.

DESCRIPTION

FIG. 1 shows a top perspective view of a roller shade bar.

FIG. 2 shows a bottom perspective view thereof.

FIG. 3 shows a front view thereof.

FIG. 4 shows a rear view thereof.

FIG. 5 shows a right side view thereof.

FIG. 6 shows a left side view thereof.

FIG. 7 shows a top view thereof; and,

FIG. 8 shows a bottom view thereof.

The broken lines in the figures depict portions of the roller shade bar that form no part of the claimed design.
